184,750

SEWING MACHINE TREADLE OR SIMILAR ARTICLE

Anthony J. Matuzas, Union, N.J., assignor to The Singer
Manufacturing Company, Elizabeth, N.J., a corpora-
tion of New Jersey

Application October 15, 1958, Serial No. 52,989

Term of patent 14 years

(Cl. D70—2)

Fig. 1 is a top perspective view of a sewing machine treadle, showing my new design.

Fig. 2 is a front elevational view of the treadle shown in Fig. 1.

Fig. 3 is a rear elevational view of the treadle shown in Fig. 1.

Fig. 4 is an end elevational view of the treadle as seen from the left side of Fig. 1.

Fig. 5 is an end elevational view of the treadle as seen from the right side of Fig. 1.

Fig. 6 is a sectional view on the line 6—6 of Fig. 1, and

Fig. 7 is a bottom view of the treadle shown in Fig. 1.

I claim:

The ornamental design for a sewing machine treadle or similar article, substantially as shown.
